US00D838259S

(12) **United States Design Patent** (10) Patent No.: **US D838,259 S**
 Samrelius (45) Date of Patent: ** Jan. 15, 2019

(54) **EARPHONE**

- (71) Applicant: **GN Netcom A/S**, Ballerup (DK)
 (72) Inventor: **Jonas Samrelius**, Stockholm (SE)
 (73) Assignee: **GN Netcom A/S** (DK)
 (**) Term: **15 Years**
 (21) Appl. No.: **29/602,627**
 (22) Filed: **May 2, 2017**

Related U.S. Application Data

- (62) Division of application No. 29/497,986, filed on Jul. 30, 2014, now Pat. No. Des. 786,834.

Primary Examiner — Paula Allen Greene(74) *Attorney, Agent, or Firm* — Altera Law Group, LLC**CLAIM**

The ornamental design for an earphone, as shown and described.

DESCRIPTION

FIG. 1 is a front upper perspective view.

FIG. 2 is a rear upper perspective view.

FIG. 3 is a front lower perspective view.

FIG. 4 is a rear lower perspective view.

FIG. 5 is a side perspective view.

FIG. 6 is a side perspective view of the other side; and,

FIG. 7 is another side perspective view.

The features shown in broken lines depict environmental subject matter only and form no part of the claimed design.
